Inventor:

B. P. McKinley

By his Attorney *John O. Sufit*

UNITED STATES PATENT OFFICE.

BENJAMIN P. MCKINLEY, OF NEW YORK, N. Y., ASSIGNOR TO HEMCO ELECTRIC MANUFACTURING COMPANY, INC., OF LONG ISLAND CITY, NEW YORK, A CORPORATION OF NEW YORK.

MULTIPLE SOCKET AND PLUG DEVICE.

Application filed July 18, 1923. Serial No. 652,272.

This invention relates to a combined multiple socket and electrical connection plug member whereby to adapt a single cut out in an electric circuit for the connection of one or two electric translating devices instead of one of said devices for which said cut outs are arranged, and it is the object of the invention to provide a combined multiple socket and separable plug device which is novel and attractive in appearance, simple and cheap in structure, durable, and with all of the parts and the electrical connections thereof united in positive insulated relation from each other into a rigid compact integral one piece structure with no possibility of the electrical connections becoming loose.

In carrying out the invention I provide a pair of metallic shell electrically connected in end to end axial relation and electrically connect a contact blade to one of the shells to extend laterally thereof to constitute a contact terminal member of a separable plug member combined with the shells. A second contact blade is arranged with means at one end to extend from the opposite faces thereof to constitute the center contact terminals of the sockets. The connected shells having the one contact blade connected therewith arranged as a unit and the other contact blade are then arranged in a suitable mold with the blade contacts in parallel and spaced relation with the end contact terminals of the one blade arranged axially of and projecting into the inner ends of the shells, when insulating material is molded about the exterior of the shells with the connection thereof with the one blade contact and the end of the other blade carrying the center contact terminals for the shells in imbedded relation in said material thereby uniting the whole into a compact integral one piece structure.

In the drawing accompanying and forming a part of this specification Figure 1 is a side elevation showing an embodiment of the invention.

Figure 2 is a longitudinal sectional view.

Figure 3 is an end elevation.

Figure 4 is a perspective view of the contact blade carrying the center terminal contacts for the shells.

Figure 5 is a perspective view of the other

contact blade showing the connection thereof with one of the shells; and

Figure 6 is a perspective view of an end contact of the sockets.

In the embodiment of the invention shown in the drawing a body of molded insulating material, such as bakelite, condensite and the like 6 has exteriorly imbedded therein a pair of terminal contact members in the form of threaded shells 7, 8, said shells being arranged in axial end to end spaced relation with the insulating material 6 molded in the space between the inner ends of the shells, as shown at 9, to constitute the end wall of the shells, the inner ends of the shells being flanged inwardly, as at 10 and 11. The insulating material is preferably arranged with an annular portion 12 to extend beyond the outer extremity of the contact members with the rough edges of said members imbedded in said material. The shells are arranged in rigid electrical connection by a pin 13 having the opposite ends shouldered for engagement in perforations in the shell flanges 10, 11 and the material of the ends upset to rivet the shells to the pin, as shown at 14, said pin being imbedded in the insulating material 6.

The device is adapted to constitute one member of a separable plug or for connection to a cut out in an electric circuit and for this purpose the insulating material is molded intermediate its ends 12 with the laterally projecting part 15, which is preferably of circular shape or may be of any other conformation to mate with the other plug member.

A contact blade 16 to constitute one of the contact members of the plug portion is electrically connected to one of the contact terminals 7 and 8, shown as the shell 7, with the connection thereof imbedded in the insulation material. To electrically connect said contact blade 16 with the shell 7 the blade is arranged at one end with an annular portion 17 (Figure 5) within which a portion of the flange 10 of shell 7 engages, as shown at 18, with the opposite end of the blade extending laterally from the insulating material.

A second contact blade 18 is bent midway

its ends, as at 19, to offset the one end of the blade relative to the other, as clearly shown in Figures 2 and 4, with the one end 20 embedded in the insulating material and 5 the opposite end projecting laterally therefrom in parallel and predetermined spaced relation to the contact blade 16. The contact blade 18 constitutes the other contact member of the plug portion. The contact 10 blade 18 at the end imbedded in the insulating material is arranged with means to constitute the end contact terminals of the shells or sockets, said means being shown as consisting of a pin 21 with the ends projecting from opposite sides of the blade and axially into the inner ends of the shells. To assure the electrical connection of the 15 end contact of an electric lamp or connection plug inserted into the shells with the 20 contact pin 21 yielding or springy contact members 22 are secured to the ends of the pin. These contact members are constructed of sheet metal with a perforation 23 at one end for mounting the same upon the ends of 25 the pin 21. After the contact plates 22 have been arranged upon the ends of the pin 21 washers 24 are placed on the pin outside of 30 said contact members and the ends of the pins upset to rivet said contacts 22 thereto when said contact plates are bent to the position shown in Figure 2. The connection of the contact plates 22 with the pin are arranged in recesses 25 in the insulating material at the inner ends of the shells whereby to prevent electrical connection between 35 said contact plates and the shells.

Having thus described my invention I claim:

1. As a new article of manufacture, a 40 combined multiple socket and plug member, comprising a pair of metallic shells arranged end to end in axial and spaced relation and in electrical connection with each other, a contact member in electrical connection with 45 one shell extending laterally of said shells, a second contact member extending laterally of said shells in parallel spaced relation to the first contact member and out of electrical connection therewith and the shells and 50 having a pin projecting oppositely therefrom axially into the shells to constitute end contacts for the shells, and insulating material molded exteriorly of the shells with

the shells and the portion of the contact members extending laterally of the shells in 55 embedding relation thereto.

2. As a new article of manufacture, a combined multiple lamp socket and separable plug member, comprising a pair of metallic shells; means to rigidly and electrically connect said shells in axial end to end and in spaced relation; a blade having an annular portion at one end and connected to a shell by engaging a portion of the latter in said annular portion with the other end of the 60 blade extending laterally of the shell; a second blade; a pin carried at one end of said latter blade with the end projecting from opposite sides thereof, said blade being arranged in parallel spaced relation to the 65 first blade with the pin extending axially of and into the shells to constitute end contact terminals of the shells; and insulating material molded exteriorly of the shells with the connection of the one blade and 70 shells and the pin carrying end of the other blade in imbedded relation thereto with the ends of the pins projecting from said material into the shells.

3. As a new article of manufacture, a combined multiple lamp socket and separable plug member, comprising a body of insulating material having a pair of electrically connected and end to end axially arranged threaded shells exteriorly surrounded by 80 said material and having the connection thereof in imbedded relation thereto; a contact blade electrically connected to a shell with said connection imbedded in the insulating material and said blade extending laterally of the material between the shells; a second contact blade imbedded at one end in the insulating material with the opposite end extending laterally therefrom in parallel spaced relation to the first blade, said 85 second blade carrying a pin at the imbedded end with the ends of the pin projecting from opposite sides of the blade to exposed position centrally of the ends of the shells; and yielding contact members attached within 90 the shells to the pins carried by the one contact blade.

Signed at Long Island City, in the county of Queens, city and State of New York, this 14th day of July, 1923.

BENJAMIN P. McKINLEY.
